UNITED STATES PATENT OFFICE

ISIDOR KITSÉE, OF PHILADELPHIA, PENNSYLVANIA, ASSIGNOR TO MINERALITE CORPORATION, OF PHILADELPHIA, PENNSYLVANIA, A CORPORATION OF PENNSYLVANIA

PRODUCING BOARD-LIKE MATERIAL WITH THE AID OF MINERAL WOOL

No Drawing.

Application filed November 21, 1929. Serial No. 408,937.

My invention relates to an improvement in producing board-like material with the aid of mineral wool.

This invention may be applied to so-called slag wool, produced from the non-metallic residue of steel or iron furnaces; or it may be applied to so called rock-wool, the natural product of rocks containing silicate and magnesia.

10 To produce a board-like material such for instance as is used for wall boards one of the suitable operations is as follows:

The mineral wool, either alone or, in conjunction with a dissolved silicate such as a silicate of sodium, potassium or other useful alkaline is intermixed with the mineral wool and the fiber, as above stated, added to the mineral wool plus dissolved silicate in a manner so that all three materials should form a homogeneous mass and then subjected in a mold to heat and pressure, whereby, a solid board-like structure is obtained. This board can then be shaped with the aid of a saw or other like tools in desired dimensions.

25 Having now described my invention, what I claim as new and desire to secure by Letters Patent, is:

1. The improvement in producing a board-like material consisting therein that the material out of which said board is fashioned, consists of mineral wool, and is provided on both surfaces with a material adapted to produce a smooth surface.

30 2. As an article of manufacture, a stiff solid building board or the like comprising a homogeneous mixture of fibrous material and a binding substance, the principal part of the fibrous material being mineral wool and the board having smooth surfaces and 35 being workable by tools into shapes as desired.

In testimony whereof I affix my signature.

ISIDOR KITSÉE.
